UNITED STATES PATENT OFFICE.

LOUIS WILE, OF MORRIS, ILLINOIS, ASSIGNOR OF ONE-HALF TO LARS HANSEN, OF MORRIS, ILLINOIS.

EAR-MUFF.

SPECIFICATION forming part of Letters Patent No. 708,446, dated September 2, 1902.

Application filed February 14, 1902. Serial No. 94,063. (No model.)

To all whom it may concern:

Be it known that I, LOUIS WILE, a citizen of the United States, residing at Morris, in the county of Grundy and State of Illinois, have invented a certain new and useful Improvement in Ear-Muffs, of which the following is a specification.

My invention relates to ear-muffs, and has for its object to provide a new and improved device of this description.

My invention is illustrated in the accompanying drawings, wherein—

Figure 1 is a view of the frame of one form of ear-muff with the covering removed. Fig. 15 2 is a view showing the completed ear-muff, the view taken from the inner side. Fig. 3 shows the ear-muff in position. Fig. 4 is a section on line 4-4, Fig. 3. Fig. 5 shows the framework of an ear-muff made adjustable. 20 Fig. 6 is a view illustrating the manner of carrying the ear-muffs.

Like letters refer to like parts throughout the several figures.

With the ordinary ear-muff there is no 25 means of keeping it in position on the ear except by a connection between the two ear-muffs, which draws them toward each other.

One of the objects of my invention is to provide an ear-muff which can be firmly attached to the ear, the muff for each ear being 30 absolutely independent in this connection.

Referring now to the drawings, I have shown in Fig. 1 a framework upon which the covering of the muff is mounted. This framework may of course be changed in construction, and I have simply attempted to show one construction by means of which my invention may be made clear. This frame consists of an outer part A, to which the covering D is attached. Associated with this outer part is a clamping device for clamping the muff to the ear. This clamping device may be varied in many particulars, and as shown in Fig. 1 consists of two parts B and C, between which the ear is clamped. These parts are movable with relation to each other and are also movable with relation to the part or frame A. The part B is made of such size that it may be passed over the ear, as shown 45 in Fig. 3, so that it comes between the ear

and the head. The part C is then pressed into the hollow of the ear, as shown in Fig. 3, the ear being clamped between B and C. Some suitable means is preferably provided for locking the parts in position. As herein 55 illustrated, this is done by the end of the part B engaging the frame A at the point A' and forming a clasp, as it were, at this point. By this arrangement the parts may be easily separated by means of the fingers. The several parts may be covered with any desired material, or the parts B and C may be left bare, if desired. Any such arrangement as may be desired along these lines can be used.

In placing the muff upon the ear the parts 60 B and C are moved away from the covering D, the ear is then slipped through the opening in the part B, and the part C is then pressed into the hollow of the ear, as shown in Fig. 4, the covering being then in the position 65 shown in dotted lines in said figure. The ear is thus clamped between the parts B and C, the covering is pressed into position, so as to be locked at the point A', and the ear-muff is then firmly attached to the ear and cannot 70 be removed except by unclamping it at A'. To remove the ear-muff, it is unclamped at A', the covering being moved to the position 75 shown in dotted lines in Fig. 4. The part C is then moved outwardly and the part B then 80 removed from the ear. A button or projection C' may be associated with C, so as to facilitate the operation. The part B is shown as pivotally connected to the part A² of the frame and preferably runs toward a point 85 where it makes contact with the other side of the frame. It will thus be seen that by means of this device the ear-muff is clamped securely upon the ear and will thus be properly and securely held in position without 90 external aid.

In order that the muff may be made to fit any-sized ear, I may make the ear-receiving opening adjustable. Any desired construction for this purpose may be used. As shown 95 in Fig. 5, the part B is provided with a movable cross-piece B', which slides along the branches of B and preferably fits somewhat tightly, so that it will be held in any position to which it is moved. It will thus be seen that 100

by varying the piece B' the size of the space in the part B may be varied, so as to accommodate it to ears of various sizes.

I have described in detail a particular construction embodying my invention; but it is of course evident that this construction may be greatly varied and that some of the parts may be omitted and others used with parts not herein shown without departing from the spirit of my invention. It is also evident that the clamping device may be greatly varied, and I have not attempted to set up the various constructions which might be used.

It will be seen that by this arrangement each ear-muff is separate and independent and there is no connection between them, as is the case with the ear-muffs now on the market. This arrangement facilitates the carrying of such muffs.

20 I have shown an arrangement in Fig. 6 whereby the muffs are always at hand and can be carried without trouble and their presence will be insured whenever needed. As illustrated in said Fig. 6, I have shown a coat, 25 which may be an overcoat, provided with pockets E E on the inner side and near the top. These pockets may be formed in any desired manner and are of sufficient size to each receive one muff. The pockets may be 30 so arranged that they are not noticeable, and the muffs may be placed therein and will always be ready for use, and they will further always be accessible and their location always known. These ear-muffs may be sold 35 directly with the coats, thus making them a selling point for the coats, as the convenience of this arrangement will be readily appreciated. The muffs may be loose in the pockets or they may be attached thereto by 40 means of a suitable cord.

I claim—

1. An ear-muff, comprising a suitable covering for the ear, a clamping device associated with said covering and adapted to clamp it to 45 the ear, so that it will be held in proper position, said clamping device adapted to be moved out of the plane of the covering to release the ear.

2. An ear-muff, comprising a suitable frame, 50 a covering therefor, a clamping device movably connected with said frame and adapted

to clamp the ear, so as to hold the muff in position, said clamping device comprising a part or loop through which the ear passes and a second part co-operating therewith.

55

3. An ear-muff, comprising a frame, a suitable covering therefor, a clamping device attached to the frame and comprising two parts between which the ear is clamped, one part engaging the back of the ear and the other 60 the outer face thereof.

4. An ear-muff, comprising a frame, a suitable covering therefor, a clamping device attached to the frame and comprising two parts between which the ear is clamped, said clamp- 65 ing parts movably connected to the frame, one of said parts engaging the frame when in its clamping or holding position so as to hold or lock the parts in said position.

5. An ear-muff, comprising a suitable frame, 70 a covering therefor, and an adjusting device for adjusting the size of the ear-receiving opening of the muff, so as to fit different ears, said adjusting device normally fixed during the use of the muff, the ear-receiving 75 opening remaining unchanged when the proper adjustment is secured.

6. An ear-muff, comprising a frame, a covering therefor, a clamping device comprising two parts movably connected with said cov- 80 ering and between which the ear is clamped, and an adjustable part connected with one of said parts so as to adjust the ear-receiving opening of the muff to fit different-sized ears.

7. An ear-muff, comprising a suitable frame, 85 a covering therefor, a two-part clamping device associated therewith and adapted to clamp the muff to the ear, both parts of said clamping device movable in a plane at an angle to the frame of the muff.

90

8. An ear-muff, comprising a frame, a covering therefor, a two-part clamping device pivotally connected to said frame, one within the other, one adapted to receive the ear and engage the back thereof and the other adapted 95 to be moved to engage the outer face of the ear, so as to hold the parts in position.

LOUIS WILE.
